UNITED STATES PATENT OFFICE

OLIVER M. MOWAT, OF YOUNGSTOWN, OHIO

APPARATUS FOR SERVING TUBE FINISHING MACHINES

Application filed August 31, 1929. Serial No. 389,733.

This invention pertains to apparatus for handling tubes, and more particularly it relates to an apparatus for simultaneously serving a plurality of tubes endwise into a plurality of end finishing machines.

In the manufacture of tubes, it is necessary to cut the rough ends off the unfinished tubes and then thread or otherwise prepare them so that they can be joined together either before or after they are shipped. Finishing operations of this character require either manual or mechanical manipulation of the tubes to serve them to and remove them from various kinds of finishing machines, and, as in the manufacture of other articles, it is desirable to reduce to a minimum the labor necessary for such handling and manipulation so as to increase production to a maximum and at the same time lower the cost of manufacture as much as possible, all of which is dependent to a large extent upon the efficiency of the apparatus employed for such purposes.

The primary object of this invention generally stated is to provide simple, efficient and economically operable tube handling apparatus for serving a plurality of tubes simultaneously into a plurality of end finishing machines and for doing so in such a way as to increase the speed of production of the machines, at the same time reduce the manual labor necessary to their operation, and thereby lower the cost of manufacture of the tubes.

A more special object is to provide a machine of the above character which is adapted to move a plurality of tubes laterally in spaced parallel relation with each other into registration with a plurality of end finishing machines, and then simultaneously feed them endwise into the machines, and, after they have been operated upon, carry them therefrom, the apparatus being also adapted to permit finished tubes to be discharged from and unfinished tubes to be loaded on it while the finishing machines are operating upon tubes previously fed to them.

These and other objects, as well as the novel features and advantages of the invention, will become more apparent when the following detailed description is read in conjunc-

tion with the accompanying drawings, of which Fig. 1 is a plan view of an apparatus for serving a plurality of unfinished tubes to and discharging them from a plurality of finishing machines, the apparatus being constructed in accordance with this invention; Fig. 2 a side view and Fig. 3 an end view of the same; Fig. 4 an elevation to enlarged scale of a pipe supporting rest showing the way it is mounted; Fig. 5 a detail sectional view on the line V—V of Fig. 1; Fig. 6 a side view and Fig. 7 a front view of a guide positioned adjacent the serving end of a movable tube-supporting rack; Figs. 8 to 13 plan views showing different positions of the tube supporting rack with respect to the finishing machines during a cycle of operation; and Figs 8a to 13a end views corresponding with Figs. 8 to 13, respectively.

Referring now to the drawings wherein the invention is illustrated in connection with a tube serving apparatus for feeding a plurality of tubes into a plurality of end finishing machines, 1 designates generally a main supporting or base frame for the apparatus made up of transverse and longitudinal cross and side members 2 and 3, respectively. To facilitate moving this frame back and forth in a sidewise or lateral fashion it is equipped at the opposite ends of its cross members 2 with track wheels 4, that rest upon rails 5, and to produce such movements mechanically, a mechanically operated pusher rod 6 is attached at 7 to the center of one longitudinal side frame member 3. Although not shown, this pusher rod may be actuated in any convenient manner, as by a rack and pinion, a hydraulically-operated device or other means of a well known construction capable of producing the desired movements, and to positively limit the sidewise movements of frame 1 in either direction, blocks 8 may be mounted at the ends or other points along the length of the tracks.

On top of base frame 1 there is movably mounted a tube-supporting rack 9 formed of a pair of longitudinal side and transverse cross members 10 and 11, respectively. This rack is preferably made somewhat shorter and narrower than frame 1 and is equipped at

the ends of side members 10 with wheels 12 which move upon rails 13 secured to the tops of the cross members 2 of frame 1. For mechanically effecting the endwise movement of rack 9, a hydraulic or other fluid pressure cylinder 14 is secured to the front and center transverse member 2 of frame 1, as shown in Figs. 1 and 3. In this cylinder there is provided the usual piston, not illustrated, which is connected by means of a rod 15 to the center of the rear cross member 11 of rack 9. Hence, in accordance with the control of the hydraulic pressure in cylinder 14, rack 9 may be moved toward or from a finishing machine in the front of the serving apparatus.

In order to hold the tubes in spaced parallel relation with each other on top of rack 9 so as to properly guide them into finishing machines located in front of the rack, such for example as the threading machines 16 and 17 shown in Figs. 8 to 13, there are provided a plurality of tube rests 18 having receiving openings 19 in their tops. These are arranged at the front and back ends of the rack and spaced from each other a distance equal to that between the centers of machines 16 and 17, and are mounted for vertical movements so that the apparatus can be used for different size tubes, and also so that the rests can be lowered below the tubes to allow rack 9 to be moved while tubes are being operated upon by the finishing machines. For effecting simultaneously vertical movements of all of rests 18 at each end of the rack, they are all rigidly secured between a pair of channels 21 mounted for vertical movement in end cross members 11. As illustrated more particularly in Figs. 2 and 5, the transverse or cross members 11 of rack 9 comprise a pair of spaced channels 22, and between them channels 21 are arranged, the latter being sufficiently smaller than the space between channels 22 to permit them to move therein with ease. For raising and lowering rest-supporting members 21, legs 23 (Figs. 4 and 5) are secured between channels 21 near the opposite ends thereof and extended below the surface of cross members 11 where they are rested upon the laterally movable wedges 24 that in turn are supported in U-shaped straps 25 attached to the bottoms of cross member 11, the bottoms of the legs being tapered at 26 to facilitate their movement on the inclined portions of the wedges. In order to move these wedges laterally with respect to legs 23 so as to raise and lower the rests as desired, they are each connected to a suitable hydraulic or equivalent apparatus similar to that employed in connection with the movement of the rack 9, each apparatus comprising a cylinder 27 (Fig. 3) in which the usual piston is arranged, and a piston rod 28 connecting the piston with the wedge. Hence, by varying the pressure in the cylinders the wedges may be forced forwardly to raise the

rest supports, or backwardly to permit the supports to be lowered by gravity. To limit the movements of the wedges, there are adjusting nuts 29 on rods 31 connected to the pistons, and, for preventing the support members 21 from moving endwise in cross member 11, guides 32 formed integrally with the end rests 18 extend downwardly through holes provided in the centers of guide blocks 33 secured to the bottoms of channels 22. Through this arrangement, as appears most clearly in Figs. 4 and 5, rests 18 may be readily adjusted for supporting different size tubes in registration with the finishing machines.

In order to facilitate the arrangement or positioning of the tubes on rack 9 in such a way that they will all enter the finishing machines correctly when the rack is moved into its feeding position, a guide bar 34 supported on legs 35 is provided, see Figs. 6 and 7. This guide, as illustrated more particularly in Figs. 8 to 13, is arranged in front of rack 9 on the side of the finishing machines from which the tubes are fed and is positioned in alignment with the cutting tools of the finishing machines. Consequently through its use the tubes being worked upon may be accurately arranged upon rack 9 for entrance into the finishing machine in a manner appearing more clearly hereinafter. It is the usual practice to mark the ends of tubes as they are produced to indicate the amount of scrap or waste which must be removed before the tubes are finished. When tubes marked in this manner, but not cut are being handled by the apparatus, guide bar 34 is preferably positioned below the bottoms of the tubes rested on the rack, see Fig. 7, but when smooth ended or tubes from which the scrap ends have previously been removed are being handled it may be raised so that the tubes will abut against it as the rack is moved forward.

As will be readily appreciated by those skilled in the art, the operation of the hydraulic devices for moving various parts of the apparatus, as explained above, may be effected in numerous ways, either by manually or automatically controlled valves, whereby the movements may be selectively produced in the manner to be described hereinafter in connection with the explanation of the operation of the apparatus, but because the control of these elements in a particular way forms no part of this invention, and because such control mechanism is so well known in the art, it is deemed unnecessary to illustrate and describe it.

The operation of the apparatus will now be explained in conjunction with Figs. 8 to 13 and 8a to 13a, inclusive, wherein it is illustrated as being employed for serving two tubes simultaneously into a pair of end finishing devices, schematically shown as threading machines 16 and 17. Figs. 8a to

13a are elevations of the apparatus shown in Figs 8 to 13, looking toward the threading machines which are stationary. To begin the operation, base frame 1 is moved so that the two forward tube rests 18 on rack 9 are in alignment with machines 16 and 17, and rack 9 is moved back from these machines so that tubes can be loaded thereon without fouling them, as shown in Fig. 8. On the initial loading, tubes 36, 37, 38 and 39 are arranged on rests 18 on the rack with tubes 36 and 37 correctly positioned for engagement by the threading machines. Wedges 24 are then set to properly center the tubes horizontally for entrance into the machines. Thereafter, the piston in cylinder 14 is operated to move rack 9 to the position shown in Fig. 9, feeding tubes 36 and 37 simultaneously into machines 16 and 17. While the threads are being cut on these tubes, the ends of tubes 38 and 39 are lined up with guide 34 for subsequent entrance into the threading machine. After the ends of tubes 36 and 37 have been finished, rack 9 is moved back to its original position, and base frame 1 moved forwardly to bring tubes 38 and 39 into alignment with machines 16 and 17, as shown in Fig. 10. Rack 9 is then again moved toward the finishing machines, as viewed in Fig. 11, to feed tubes 38 and 39 thereinto. While these tubes are being operated upon, pressure cylinders 27 are operated to move wedges 24 to lower rests 18 below the top of rack 9, as indicated in Fig. 11a. With the rests thus lowered, tubes 36 and 37 are moved off rack 9 onto racks 41 positioned forwardly of rack 9, as seen in Figs. 10 and 11, from whence they may be conveyed to another set of finishing machines to have their other ends threaded or otherwise operated upon. With rests 18 still lowered so that they will not foul tubes 38 and 39 which are engaged by the threading machines, base frame 1 is returned to its initial position, carrying rack 9 to the position shown in Fig. 12. Rests 18 are then raised again, as shown in Fig. 13a, rendering the apparatus ready to repeat the cycle of operation, which is initiated by placing new tubes 42 and 43 on the rests 18 at the rear of rack 9, and lining them up with guide 34 for entrance in the threading machines while tubes 38 and 39 are being finished.

While the serving apparatus illustrated is shown in connection with only two finishing machines, it will be readily appreciated that the number of finishing machines is not so limited, but may be one or any number, depending upon the speed of production desired. The operation of the serving and finishing machines may be effected automatically by well known hydraulic, electric or other means, so that each operation will be timed in the proper order to automatically produce cycles of operation in the manner described.

According to the provisions of the patent

statutes, I have explained the principle and operation of my invention, and have illustrated and described what I now consider to be its best embodiment. However, I desire to have it understood that, within the scope of the appended claims, the invention may be practiced otherwise than as specifically illustrated and described.

I claim as my invention:

1. In combination with a tube finishing machine, of apparatus for serving tubes to and carrying them from said machine, said apparatus comprising a movable mounted rack adapted for feeding tubes in an endwise fashion into and discharging them from said machine, said rack being provided at its opposite ends with vertically movable tube rests which engage the tubes carried upon the rack, and means for raising said rests to center the tubes in the finishing machine and for lowering them out of engagement with the tubes when such are engaged in the finishing machine to permit lateral movement of the rack and frame for reloading and unloading the rack without interrupting the continuous operation of the finishing machine.

2. In combination with a tube finishing machine of apparatus for serving tubes to and removing them from said machine, said apparatus comprising a rack movable longitudinally and transversely with respect to the axis of said machine for feeding tubes endwise into and discharging them from the machine, said rack being provided at its opposite ends with vertically movable tube rests for holding the tubes in place on said rack, movable wedge shaped supports being mounted below said rack for vertically supporting said rests, and means for moving said wedges to raise or lower said rests to center the tubes in the finishing machine and for lowering them out of engagement with the tubes when such are engaged in the finishing machine thereby permitting lateral movement of the rack and frame for reloading and unloading the rack without interrupting the continuous operation of the finishing machine.

3. In combination with a plurality of adjacent tube finishing machines of apparatus for serving a plurality of tubes to and discharging them from said machines, said apparatus including a longitudinally movable tube supporting rack adapted for moving the tubes endwise into and away from said machines, a plurality of tube rests disposed at the opposite ends of said rack for holding the tubes in spaced parallel relation thereon, said rests being rigidly secured to cross members mounted for vertical movement in the opposite ends of the rack, a plurality of wedge shaped supports mounted beneath and engaging the opposite end of said cross member, and means for moving said supports to raise and lower the tube rest to horizontally

100

105

center tubes of different size supported on the rack in the finishing machines.

4. In combination with a plurality of adjacent tube finishing machines of apparatus positioned in front of the machines for simultaneously moving a plurality of tubes laterally into feeding alignment therewith, endwise thereto and therefrom and then laterally therefrom, said apparatus comprising a base frame adapted for lateral movement and having means attached thereto for mechanically moving it in opposite directions, a tube supporting rack mounted for endwise movement on said base frame, mechanically operable means connected between said rack and said frame for moving said rack toward and away from said machines a preselected distance, means on top of said rack for holding a plurality of tubes in spaced parallel relation thereon, and means for raising said last mentioned means to center the tubes as they are fed into said machines, and for lowering them to permit the rack to be moved laterally under the tubes supported theron when engaged by the finishing machines without disturbing the tubes, thereby facilitating the unloading and reloading of the tube rack.

5. In combination with a tube finishing machine, of apparatus for serving tubes to and removing them from said machines, said apparatus comprising a laterally movable base frame, a tube-supporting rack mounted for endwise movement upon said base frame, a plurality of disappearing tube-engaging rests mounted on said rack to center the tubes in the finishing machine, a guide disposed in front of said rack and frame for use in aligning the tubes in proper position on the rack, means for raising and lowering said rests from a point below to a point above said rack and back again and means for moving both the base frame and the tube-supporting rack in opposite directions to move tubes supported by said rack laterally into alignment with said guide and finishing machine, then endwise to and from said machine and then laterally therefrom.

In testimony whereof, I sign my name.
50 OLIVER M. MOWAT.
